UNITED STATES PATENT OFFICE.

NELSON C. NEWELL, OF SPRINGFIELD, MASSACHUSETTS.

BUTTON.

SPECIFICATION forming part of Letters Patent No. 279,002, dated June 5, 1883.

Application filed December 6, 1882. (No model.)

To all whom it may concern:

Be it known that I, NELSON C. NEWELL, a citizen of the United States, residing at Springfield, in the county of Hampden and State of Massachusetts, have invented new and useful Improvements in Buttons, of which the following is a specification.

This invention relates to an improved construction of a compound button, consisting of a cloth-face button having the usual shank of textile material, a back and rim of vegetable ivory, plastic material, or other similar substance, and devices for uniting said cloth-face button and back and rim, the object being to provide such a construction of the latter and of said uniting devices as, when combined with said button and shank, will prevent said back and rim from being broken when the parts of said compound button are secured to each other in process of manufacture, and by reason of shrinkage thereof subsequent to the completion of said button.

This invention is in the nature of an improvement upon my Patent No. 206,348, of July 23, 1878, to which reference may be had.

In the drawings forming part of this specification, Figure 2 is a view in transverse section of a compound button constructed according to my invention. Fig. 1 is a rear plan view. Fig. 3 is a view, partly in section, showing the parts before being locked together. Fig. 4 is a face view. Fig. 5 is a view of the uniting-eyelet, and Fig. 6 is a plan view of the washer.

In the drawings, *m* is the cloth-faced button. *h* is the back and rim. *v* is the uniting-eyelet. *o* is the washer.

The cloth-face button *m* is of the ordinary construction, having a shank, *c*, of textile material, whereby the button is sewed to a garment, excepting that an eyelet, *v*, is secured to the back collet thereof by having its flange clamped under the latter, and said shank *c* projects through the latter, as in Figs. 2 and 3. Said eyelet is, as shown in Fig. 5, of the ordinary description, having a cylindrical body and a flange. The washer *o* is a flat ring, as shown in Fig. 6, and is of a diameter exceeding that of the opening through the back and rim *h*, and of a flange which is turned

down upon it, as shown in Figs. 1 and 2, which flange is formed by forcing one end of said eyelet outward and downward in the usual way.

The back and rim *h* is constructed from either vegetable or animal ivory, plastic material, or other similar substance, and is finished in suitable colors, and is adapted to receive within its shell-like form said cloth-face button *m*. Said part *h* is perforated, as shown, to allow the aforesaid eyelet and the shank *c* within the latter to project through it, as in Fig. 3.

The aforesaid materials, as well as others of a similar nature from which said parts *h* are made, are subject to more or less shrinkage after being finished ready to be attached to the button *m*, and subsequent thereto, and when they are combined with the parts shown in said patent, and constructed as therein described, and are permitted to shrink upon a rigid, or nearly so, central fastening, they frequently break, ruining the button, and to obviate breakage from said cause the perforation in said back and rim is made larger, or of greater diameter than that of the body of the eyelet *v*, which passes through it, so that any shrinkage movement of that part of the back *h* surrounding said eyelet shall not be met by any obstruction which can cause said breakage. Furthermore, if said perforation in said back *h* be no larger than the eyelet *v*, the final flanging or heading down of the latter in making the compound button often causes the back to break, since the act of flanging the end of the eyelet tends to force that part of the body thereof adjoining said flange outward against the borders of the eyelet-hole in said back; but enlarging said hole obviates said danger of breakage from this cause.

The washer *o*, in uniting the aforesaid parts, as in Fig. 3, is placed over the end of the eyelet *v* and upon the back *h*, and said eyelet is then flanged or set over onto said washer, as in Fig. 2, whereby the said button *m* and said back are securely fastened together, but in such a way as to provide for a certain amount of shrinkage movement, as above described, for said back. By the interposition of said washer between the flange of the eyelet and

said back there is less frictional resistance to the shrinkage movement of the latter than when the eyelet is flanged directly against the back.

5. What I claim as my invention is—

The within-described compound button, consisting of the button *m*, provided with the shank *c*, the eyelet *v*, secured to said button

m, the back and rim *h*, having a perforation greater than the diameter of the body of said eyelet, and the washer *o*, combined and secured together substantially as set forth.

NELSON C. NEWELL.
